ATTORNEY.

UNITED STATES PATENT OFFICE.

HARVEY H. LIGHTLE, OF SYRACUSE, NEW YORK.

PROTRACTOR.

1,096,511.

Specification of Letters Patent.

Patented May 12, 1914.

Application filed June 9, 1913. Serial No. 772,500.

To all whom it may concern:

Be it known that I, HARVEY H. LIGHTLE, a citizen of the Dominion of Canada and a subject of the King of Great Britain, residing at Syracuse, in the county of Onondaga and State of New York, have invented certain new and useful Improvements in Protractors, of which the following is a specification.

10 My invention relates to improvements in draftmen's and mechanics' protractors, and has for its object to provide a movable graduated protractor or segment, having two straight rulers or drawing sides arranged at right angles to each other, and which permit the drawing of angular lines in any direction without hindrance from any of the supporting parts.

15 A further object is to provide means for determining or calculating the degree of any angle, as well as the dividing of a circle into the desired number of parts. And a further object is to provide novel and simple means for extending the straight or drawing sides 20 of the instrument.

25 These objects are attained by the means described in the annexed specification, and illustrated in the accompanying drawing, in which—

30 Figure 1 is a plan view; showing by full and dotted lines the construction, arrangement and operation of my complete device. Fig. 2 is an edge view of the same. Figs. 3 and 4 are respectively a plan and an edge 35 view of the extension blade or ruler. Fig. 5 is an enlarged sectional view taken substantially on line 5—5 of Fig. 1; showing the construction of the pivot which supports the movable protractor. Fig. 6 is an enlarged 40 sectional view taken on line 6—6 of Fig. 1; showing the construction and arrangement of the adjusting and clamping means. Fig. 7 is a plan view of the movable protractor.

45 In the drawing, 2 represents the protractor which preferably comprises one part, having the center cut away, and having similar ruling sides or edges 3 and 4, which are arranged to intersect at right angles to each other. The rulers 3 and 4 are connected at their corresponding ends, by means of an integral arched protractor 5, which preferably comprises a quadrant, graduated from 0° to 90°, and the graduations are numbered so as to read from zero from the 50 opposite ends of the part 5. The movable triangular part 3—4—5 is pivoted, and is

therefore oscillatable, by means of a screw or stud 6 and a nut 6' to one end of an arm or bracket 7, and is thus allowed free movement or swing in opposite directions, for 55 drawing lines along the edges 3 and 4, at any angle within a radius of 180°. The bracket or support 7 is preferably formed A-shaped, as shown, so as to give it adequate strength, and its opposite end is rigidly secured to a base 8 in any suitable manner, as by rivets 9. The base 8 is preferably disposed at right angles to the longitudinal center of the bracket 7, and its edge 8' is intended to rest against, or slide freely in opposite directions along a T-square, or other 60 suitable instrument (not shown). The quadrant 5 is provided with a concentric slot 10, in which is disposed a screw 11, which is engaged by a thumb-nut 12. The slot 65 10 is of suitable length for allowing the protractor to be swung in opposite directions on the pivot 6, as indicated by the dotted lines in Fig. 1, and it may be readily secured in any desired position by the tightening up 70 of the thumb-nut 12. The base 8 is provided with a single graduation or mark 13, having an arrow point or head which points to the graduations of the quadrant 5. When the movable protractor is set in the position 75 shown in full lines in Fig. 1, the mark 13 points to 45 degrees on the quadrant, and the draftsman may draw a line along either of the edges 3 and 4 at an angle of exactly 45° to the base 8. When the protractor is 80 swung or moved to the right as far as allowed by the slot 10, and screw 11, a horizontal line may be drawn along the edge 4, while a vertical line may be drawn along the edge 3. And when the protractor is 85 swung to the left the full distance, a horizontal line may be drawn along the side 3 and a vertical line may be drawn along the side 4 (see dotted lines in Fig. 1).

90 It is sometimes necessary to draw lines of 100 greater length than the edges 3 and 4, and in order to meet such a contingency, I provide an extension bar or part 14, which is preferably made in the form shown in Figs. 1, 2, 3 and 4. The extension is provided 105 with a longitudinal slot 15 in its offset portion 14' to receive a thumb-screw 16, the threaded portion of which passes through the slot 15 and screws into a perforation 16' 110 near the intersection of the rulers 3 and 4. The thumb-screw 16 is employed for holding the bar 14 in place, and also serves as a

pivot for allowing the extension to be swung in opposite directions for extending the lines. 17 represents a second thumb-screw which passes through a perforation 17' formed near the end of the portion 14' of the extension, and this screw engages corresponding threaded perforations 18 in legs or parts 3 and 4.

In Fig. 1 I have shown the blade 14 in full lines set for extending a line drawn along the side 3. To shift and set the blade 14 for extending a line drawn along the side 4, the thumb-screw 17 is first unscrewed and removed, and then the thumb-screw 16 is loosened sufficiently to allow the blade 14 to be drawn outwardly away from the protractor to the extent allowed by the slot 15. The blade 14 may then be swung around until it alines with the ruler 4, after which it should be moved in the opposite direction the full length of the slot, which will allow the screw 17 to be applied to the other perforation 18. By this means I am able to provide for extending the angular lines in either direction in a quick and ready manner and accomplish the extension work with a common blade or ruler. For ordinary work the extension 14 may be dispensed with entirely. The portion 14' of the extension is preferably beveled on its opposite sides so as to prevent unnecessary thickening of the drawing edge at the point where the parts overlap.

By constructing and arranging my oscillatable drawing instrument as herein shown and described, a draftsman may draw lines in any direction along either of the rulers 3 or 4, as well as at right angles to another line, with perfect freedom and without liability of his pen or pencil coming in contact

with either the bracket 7 or the base 8. And furthermore it is a particular object of the present invention to provide a combined protractor and drawing instrument which may be used and moved freely along a T-square or other part while the ink is still wet without danger of marring or blurring the work. By the use of my improvement, a draftsman may draw ink lines in rapid succession, and slide the instrument from one position to another and not be required to pick up the instrument and replace or readjust it after each line is drawn.

It is obvious that some changes or modifications may be made in the parts and in the arrangement of the same, within the scope defined by the appended claim without departing from the spirit of my invention.

Having thus described my invention, what I claim as new and desire to secure by Letters Patent, is—

In a device of the class described, the combination with a supporting frame, of a protractor pivotally connected to the supporting frame, one of said parts having a graduated arcuate portion and the other of said parts having an index adapted to register therewith, said protractor including two ruling edges extending at an angle to each other, and an extension member adjustably connected to the protractor and adapted to be adjusted to form a continuation of either of the ruling edges of the protractor.

In testimony whereof I affix my signature in presence of two witnesses.

HARVEY H. LIGHTLE.
